UNITED STATES PATENT OFFICE.

HENRY F. LOEWER, OF ROCHESTER, NEW YORK.

LAST.

1,182,391.

Specification of Letters Patent.

Patented May 9, 1916.

Application filed September 15, 1915. Serial No. 50,808.

To all whom it may concern:

Be it known that I, HENRY F. LOEWER, a citizen of the United States, and resident of Rochester, in the county of Monroe and State of New York, have invented certain new and useful Improvements in Lasts, of which the following is a specification.

This invention relates to lasts of the divided type, such as may be shortened 10 prior to their introduction into, or removal from, a shoe by a relative movement of the fore-part and the heel-part.

In the designing and manufacture of shoes it is quite common to make the heel-parts of similar form and dimensions, regardless of changes in the styles and shapes of the fore-parts, so that the lasts for the various styles are likewise similar in their heel-parts. Accordingly, it has been proposed to render the parts of the last detachable and interchangeable, so that in changing from one style to another it is necessary 20 only to change the fore-part of the last, the same heel-part being used throughout, and economy being thus secured in the provision of the necessary lasts.

The object of the present invention is to produce a last, capable of use in the manner above described, in which the means by 30 which the parts of the last are secured together have simple and convenient provision for detaching the fore part from the heel-part. To this end I propose to employ one or more spring-pressed plungers 35 mounted in, and movable transversely with respect to, the fore-part of the last, these plungers acting as the pivots or fastening-devices by which the fore-part is attached to the hinge-plate, link, or other connecting- 40 member by which the fore-part and the heel-part of the last are held in their operative relation. By retracting these plungers they may be readily disengaged from the connecting-member, whereupon the fore- 45 part can be detached from the heel-part, and another fore-part quickly and easily substituted.

In the accompanying drawings, Figure 1 is a longitudinal vertical section of a last 50 embodying the present invention; and Fig. 2 is a partial transverse section through the fore-part of the last, on a larger scale than Fig. 1.

The invention is applicable to divided 55 lasts of various constructions and modes of operation, but it is shown, for convenience,

in a last in which the fore-part and heel-part have a relative sliding movement along an inclined section-plane at the waist of the last. The heel-part 5 and the fore-part 6 ⁶⁰ are shown as joined by a connecting-member in the form of a sheet-metal plate 7, this plate being seated in narrow slots in the two parts so as to retain them firmly in their proper relative positions. To permit the ⁶⁵ sliding movements of the parts, the plate 7 is pivoted to the heel-part 5 on a pin 8. In order to actuate the plate 7, and also to lock it against accidental movement, it is provided with gear-teeth 9 which mesh with a ⁷⁰ worm 10. The worm is arranged to turn in a perforation in the heel-part of the last, and is integral with a socket 11 which not only serves as the thimble or socket to receive a jack-post upon which the last may ⁷⁵ be placed, but is also formed with a square or otherwise non-circular opening, so that the worm may be rotated by the introduction of a suitable instrument into the socket. This arrangement constitutes no part of the ⁸⁰ present invention, but is disclosed in U. S. Patent #873,060, granted to me December 10, 1907.

The connecting-member 7 is movably attached to the forepart 6 by means of two ⁸⁵ pivot-pins 12 and 13, which work in slots in the plate. These slots are formed, as disclosed in my said patent, in such a manner as to hold the fore-part closely in contact with the heel-part throughout all parts of ⁹⁰ their relative movement, and thus to secure a straight-line or sliding movement between the parts of the last.

The invention resides particularly in the form and arrangement of the pivots 12 and ⁹⁵ 13. As shown particularly in Fig. 2, these pivots are in the form of spring-pressed plungers, arranged to slide in metal sockets 14 which are driven tightly into transverse perforations in the fore-part. Each plunger is pressed inwardly by a coiled spring ¹⁰⁰ 15, this movement being limited by a stem 16, which passes through an opening in the outer end of the socket-member and is headed to limit its inward movement. Each ¹⁰⁵ perforation is provided, on the opposite side of the plate 7 from the socket-member 14, with a sleeve 17 which receives the end of the plunger, when the latter is in engagement with the plate 7, and thus supports ¹¹⁰ the plunger firmly against lateral movement.

In the normal operation of the last the spring-pressed plungers act precisely in the same manner as the stationary or permanent pivots heretofore employed in the 5 same connection. When the fore-part is to be disengaged from the heel-part, however, it is necessary merely to introduce a suitable instrument through the sleeves 17, so as to depress the plungers out of engagement 10 with the plate 7, whereupon the plate may be withdrawn from the plungers and the heel-part thus disengaged from the fore-part.

I claim:—

In a divided last, the combination of a 15 heel-part; a fore-part; a connecting-member by which said parts are held in operative relation; a pivot-pin, on which the connecting-member moves, mounted to slide laterally in one part of the last; and a spring 20 for holding said pin normally in engagement with the connecting-member; the pivot-pin being retractable to permit detachment of one of said parts of the last from the other.

HENRY F. LOEWER.
